REFRIGERATOR CONSTRUCTION

Application filed December 7, 1925. Serial No. 73,583.

This invention relates to refrigerator construction and more especially to a construction having particular utility in relatively small or portable refrigerators for domestic use.

The use of ordinary wood wall construction in devices of this sort has many disadvantages. It is not a satisfactory heat insulator and the heat transmission which it permits, 10 decreases the efficiency of the refrigerator. These wood wall constructions, as heretofore employed, are not durable and they are subject to moisture getting into and opening the joints. They are hygroscopic and subject to 15 warping and getting out of shape. The metal linings usually employed therewith are heat conductors rather than insulators and are subject to corrosion and rusting and their life is relatively short. Furthermore, these structures 20 are not hermetically sealed. The outside finishing quickly wears off and because of the warping and getting out of shape which occurs, the doors in time fail to close properly, which still further decreases the efficiency.

25 In endeavoring to overcome these disadvantages, various constructions have been provided, but the increased cost, weight and bulkiness, has usually offset the other advantages attained.

30 In constructions in which the walls are provided with fillings of insulation such as ground cork or the like, the cost is higher and the insulating medium is not employed structurally, nor does it in any way strengthen the 35 structure of the refrigerator. Light shells are easily damaged and metal has the disadvantages already referred to.

It is the object of my present invention to 40 provide a generally improved, simplified, compact and inexpensive construction that will better serve the purpose for which intended, more particularly a better insulated, more sanitary and more durable construction of better appearance, a less expensive, hermetically sealed, waterproof construction 45 having great strength and rigidity, and a construction which will not warp or get out of shape and in which the doors will always fit properly.

50 To these ends, I provide for making up the

walls of the refrigerator of a solid homogeneous construction composed preferably of several thicknesses of suitable insulating fiber board, with the layers preferably lying one outside the other from the inside to the outside of the wall and bound or bonded together by a cementitious binder impervious to water. The insulating material forms the structural part of the refrigerator, providing a self-supporting homogeneous wall construction in which packed spaces, hollow formations and metal with its conductivity may be entirely eliminated.

The outside may be covered with a waterproof nonmetallic coating for finishing and hermetically sealing the exterior, and the inside may be lined with a waterproof nonmetallic coating for finishing and hermetically sealing the interior. These coatings preferably impart the desired wearing qualities 70 and the outside coating is adapted to provide a permanent finish of any suitable color.

In my co-pending application, Serial No. 73,584, filed December 7, 1925, I have disclosed an improved unitary refrigerating unit 75 and a refrigerator construction adapted to receive the same. The present invention is particularly adapted for embodiment in the refrigerator construction disclosed in that application and shall be disclosed herein as embodied in that construction, although it is, of course, not limited thereto.

The invention is illustrated in the accompanying drawings, in which:—

Fig. 1 is a front elevational view of a refrigerator embodying the present invention;

Fig. 2 is a side elevation of the same;

Fig. 3 is a vertical section taken on the line 3—3 of Fig. 2;

Fig. 4 is a fragmentary vertical section 80 through one of the upper corners of the refrigerator;

Fig. 5 is a fragmentary section through the door and adjacent jamb on the line 5—5 of Fig. 1; and

Fig. 6 is a fragmentary elevation with the outside coating partially removed to show the tension and binding means between the exterior of the insulating wall and the outside coating.

Referring to the drawings, the refrigerator shown comprises a box portion 5 supported by suitable legs 6. The device shown is of the portable household or domestic type and it has a suitable access door 8 hinged at 9 and provided with a suitable latch 10. The box portion 5 comprises a rear wall 12, side walls 13 and top and bottom walls 14 and 15, respectively. These details may, of course, all be varied within the scope of the present invention.

In making up the side walls 13, I employ several layers 16 of insulating board. The insulating board is preferably of prepared insulating material such as artificially boarded bagasse, cane fiber or the like. Insulating board of this sort when built up as will be hereinafter disclosed, has great strength and rigidity. It is easily handled, cut and fastened together and this facilitates construction. Furthermore, it is durable, relatively light in weight and relatively inexpensive, and it will not warp or get out of shape.

The layers 16 are secured together by a suitable binder 18. In the preferred embodiment of the invention, I employ casein glue or cement which is waterproof and has the desired bonding qualities, but again it is to be understood that any viscous cementitious material impervious to water might be employed. Waterproof binding layers are thus interposed between the layers of insulation and a solid homogeneous structure is provided.

The upper ends of the side walls 13 are rabbeted at 20 and the rear wall 12 may be of similar construction and rabbeted at 21. The rabbeting 20 and 21 receives the top wall 14 which is shown as being of a width less than the width of the refrigerator. The rabbeted or lap joints between the top and side and the top and rear walls which may be rabbeted similar to the side walls, are secured together by a suitable binder, preferably casein glue or cement, or any other suitable viscous cementitious waterproof material.

The rear ends or edges of the side walls 13 may be similarly joined to the opposite ends of the rear wall 14 by similar lap or rabbet joints and cementitious water proof binding material.

The bottom wall 15 is likewise made up of layers or thicknesses 25 of fiber board and the lower edges of the side walls 13 may be rabbeted at 26 to receive the adjacent ends of the bottom 15. The lower edge of the rear wall 12 may be similarly rabbeted to receive the adjacent edge of the bottom wall 15 and the joints along the bottom may be secured by casein cement or glue or other suitable cementitious water proof substance.

The fiber board or insulating walls thus form the structural part of the refrigerator. They are joined directly together and are, in

that sense, self-supporting and all frame work and other structural formation may be eliminated.

Similarly cemented in the rabbeted upper end of one side wall and in the rear wall, and extending substantially the entire length of the side wall, is a side piece 28 which may be of wood. Mounted in the top of the refrigerator is a rectangular frame comprising frame members 28 and 30 joined at their ends by suitable frame members and defining an opening in the top wall 14 for receiving the removable refrigerating unit, shown in dotted lines at 32. This opening 34 is shown and described as formed through the top wall, but it is to be understood that it may be formed through the rear, side, bottom or otherwise through the walls of the refrigerator. The refrigerating unit is assembled upon a panel or wall section 35, which, when the refrigerating unit is in place, closes the opening 34 through the wall of the refrigerator.

The bottom may have a wood frame composed of side pieces 36 joined at front and rear by suitable frame members of similar construction. The side wall 13 on the latch side of the door, has a jamb member 38 which may be of wood similarly cemented in the rabbeted end 39 of the wall 13, as shown in Fig. 5. The opposite side wall may have a similar frame piece which may be joined to the frame piece 38 by top and bottom frame members of suitable or similar construction.

Substantially the entire outer surface of the insulating wall construction may be covered with wire mesh or metal lathe. Metal fabric, such as a suitable wire mesh, is preferable, as shown at 40, and it may be stretched tightly about the outer surface of the fiber board and tacked or secured, as at 42, to the side pieces 28, 30 and 36, and to the jamb member 38 and hinge piece, where employed. It may be attached to the fiber wall or simply laid on with the attaching means omitted. This provides an effective tension tie around the entire box and, in addition, provides an anchoring or bonding means for the outside coating 43.

For the outside coating 43 I preferably employ a magnesite cement, although any suitable waterproof material may be employed. This cement is non-metallic and it may be applied in plastic condition. The coating 43 covers substantially the entire wall construction, being applied over the fiber boards 16 and wire mesh 40 and over the edges of the opening, door and base pieces. The wire mesh 40 bonds the coating firmly to the insulating structure and the coating hermetically seals the outside of the refrigerator. The bottom 14 may also be provided with a relatively thin sheet metal bottom 100 between which and the bottom fiber board wall 25, a suitable filling of insulating material or the like may

be interposed. The covering 43 may comprise a relatively rough inside coat and a finer outside coat which may be colored or finished to suit the customer. The corners of the fiber board construction are preferably removed at 46.

The inside of the box is provided with a non-metallic waterproof lining 50. I find that casein glue or cement, mixed with an inert material, such as whiting, to give it body, is suitable for this purpose, but the particular material used for this purpose may, of course, be varied. Just as the outside material provides a monolithic coating, this inside material provides a monolithic lining which may be applied in plastic form and hermetically seals the interior of the refrigerator. The particular lining material referred to may be mixed with water to bring it to the desired plastic condition for application. A solid homogeneous insulating wall construction hermetically sealed inside and outside, is thus provided. The hermetically sealing against moisture prevents any tendency to warp or get out of shape and there are no joints for moisture to enter and open.

The door 8 may be similarly made up of layers or thicknesses of fiber or insulating board 60 lined inside at 62 and coated outside at 63. The edges of the fiber board structure 60 of the door 8 are rabbeted at 65 to receive the edge or frame members 68 which may be of wood and which may be cemented therewith. The wire or metal fabric 69 of the door may be secured by tacks or brads 70 to the edge pieces 68.

The outer edges of the edge piece 68 are rabbeted or grooved at 72 and secured over these grooves 72 and extending out marginally about the edge of the door is a metal edge strip 73. The free edge of the strip 73 is turned back or beaded at 75 and interlocked with the adjacent edge of the coating 63, the metal edge thus reenforcing the edge of the door coating and the door coating at the same time reenforcing the metal strip.

The wall construction may be made up and coated inside before assembly, providing a standardized wall construction that may be cut and assembled to suit any requirements.

Within the box the refrigerator has a drip pan 80 underlying the cooling element 82 of the refrigerating unit when it is in place and an outstanding air baffle 83 causes a circulation of air over and around the cooling element of the refrigerating unit. The refrigerator may be provided internally with suitable shelves, as indicated in dotted lines at 85.

The insulating fiber board wall structure not only insulates but, in fact, forms the structural part of the refrigerator. The inside coating provides an inside wearing surface and hermetically seals the inside and the outside coating provides an outside wearing surface and finishes and hermetically seals the

outside. The walls are all of solid homogeneous insulating material construction and thin shells, hollow formations and insulating fillings without any strength or structural qualities are avoided.

The cover 90 with its ventilation openings 92 for the outside or exposed parts of the refrigerating unit is shown in Figs 1 and 2.

The lining over the bottom of the inside is preferably magnesite cement or the like for wearing qualities as well as sealing the interior.

I do not intend to be limited to the particular details shown or described.

I claim:

1. In a refrigerator construction, a wall having a permanent laminated core formed structurally of a plurality of boarded wall supporting layers of manufactured insulating boards having their side surfaces secured directly together and forming a solid wall supporting and insulating core.

2. In a refrigerator construction, a wall having a permanent laminated core formed structurally of a plurality of boarded wall supporting layers of prepared insulating material and binding means disposed in layers between the core laminations and binding said laminations with their side surfaces directly together and forming a solid structural and insulating wall.

3. In a refrigerator construction, a wall having a permanent laminated core formed structurally of a plurality of boarded wall supporting layers of insulating boards with their side surfaces secured directly together and forming a solid structural and insulating wall supporting core and a coating covering the surface of said core.

4. In a refrigerator construction, a solid wall having a permanent wall supporting and laminated core formed structurally and wholly of boarded bagasse.

5. In a refrigerator construction, a wall having a core formed structurally of a plurality of boards of prepared insulating material having their side surfaces secured directly together and forming a solid structural and insulating core and cement coatings covering the inner and outer surfaces of said core and supported thereby.

6. In a refrigerator, a permanent wall construction formed structurally of boarded fibrous insulating material self-supporting and of a strength to support a cement coating, said boarded fibrous insulating wall having an opening, wood edge pieces along the edges of said opening and permanently joined to the boarded fibrous insulating material and a waterproof cement coating applied over and supported by said boarded insulating material and over the adjacent edges of said edge pieces and hermetically sealing the wall.

7. In a refrigerator, a permanent wall construction formed structurally of boarded

fibrous insulating material, self-supporting and of a strength to support a cement coating, wood edge pieces permanently joined to and supported by said boarded insulating material, and a waterproof cement coating applied over and supported by said boarded insulating material and applied over the adjacent edges of said edge pieces.

8. In a refrigerator, a permanent wall construction formed structurally of boarded fibrous insulating material self-supporting and of a strength to support a cement coating, wood pieces joined to and supported by said boarded insulating material, metal fabric laid over the surface of said boarded insulating material over the insulating material, and a waterproof cement coating applied to and supported by said boarded insulating material over said metal fabric.

9. In a refrigerator, structural walls formed permanently of boarded laminations of self-supporting heat insulating fiber board with the laminations secured directly together to form a solid, fibrous self-supporting wall structure, an insulating waterproof cement applied externally to said walls and supported thereby and forming the exterior surface and a waterproof non-metallic coating covering the inner surface of said walls and supported thereby.

10. In a refrigerator construction, a wall having a core formed structurally of a plurality of layers of insulating board and a cementitious binder joining said layers directly together into a solid structural insulating and wall supporting core.

11. In a refrigerator construction, top, bottom and side walls each having a laminated core formed structurally and wholly of boards of prepared insulating material secured directly together and forming a solid structural and insulating core and the adjacent margins of said walls being structurally joined directly together.

12. In a refrigerator construction, top, bottom and side walls each having a laminated core form structurally and wholly of layers of prepared insulating material, the layers of the core of each wall being joined directly together by a cementitious binder with the adjacent margins of the core of each wall and joined directly together, and coatings covering the inner and outer surfaces of said core.

In witness whereof, I hereunto subscribe
55 my name this 1st day of December, 1925.

ALBERT H. MORRELL.
